UNITED STATES PATENT OFFICE.

SIGMUND F. KOHN, OF NEW YORK, N. Y.

TOY.

1,389,589.

Specification of Letters Patent.

Patented Sept. 6, 1921.

Application filed January 11, 1919. Serial No. 270,619.

To all whom it may concern:

Be it known that I, SIGMUND F. KOHN, a citizen of the United States, and resident of New York, in the county of New York and State of New York, have invented certain new and useful Improvements in Toys, of which the following is a specification.

This invention relates to toys and more especially to wind instruments comprising 10 means for producing sounds of different pitch and notes with a rattle or bell at one end and a mouth piece at the other end, the whole having the shape of a key and adapted to be otherwise decorated.

15 These and other details and the objects of the invention are more fully described in the following specification, set forth in the claims and illustrated in the accompanying drawings, wherein:

20 Figure 1 is a side elevation of the improved toy partly in section.

Fig. 2 is a sectional view through the mouth piece.

Fig. 3 is a sectional view of a modified 25 mouth piece.

Figs. 4 and 5 are modified forms of the toy.

Figs. 6 and 7 show another modified form 30 of instrument.

35 The toy is of the nature of a whistle or flute with the tube 10, a ring 11 and a mouth piece 12, the latter being tangential to the tube and terminating at the slot 13 so that the blast of air is forced into the same and

35 the tube when it is desired to produce a musical sound. The ring 11 is a circular tube communicating with the tube at 13 and having perforations 14 comprising an octave of notes and adapted to be closed by the

40 fingers of the operator and the appropriated one opened for the desired note. A loop 15 is provided at the upper end of the ring for hanging or to decorate the device, while within the ring is a rattle or bell 16 mounted on the stem 17 and divided into two sections and containing a ball 18.

45 As the sound travels around the ring, the blast, when released will cause a different sound at each opening 14 on account of the length of travel and vibrations, and songs may be played as with a flute.

The mouthpiece 12 may be provided with one or more notches to simulate the flange of a key, or if found desirable the tangential 50 mouthpiece may be dispensed with and the piece 18, like that shown in Fig. 3, could be

adopted for convenience of operating the instrument.

In the form of toy shown in Figs. 4 and 5 the perforations 14 are made in the tube 60 10 and the ring is left plain and the bell is soldered within the same, but in the latter view the tube is provided with the telescopic section 19 to be slid in and out to produce variations of the note.

65 The ring 11 in Fig. 1 is a continuation of the tube and its extreme end is closed by the wall 20 to which the stem 17 is secured, but it is evident that the bell or rattle 16 may be soldered or otherwise secured to the ring as 70 shown in the other views.

75 It is obvious that the parts may be otherwise arranged or modified without departing from the essential features above described or the scope of the appended claims.

Another form of the instrument is shown as a modification in Figs. 6 and 7 where the tube 20 is a mouthpiece with the inlet 21 and outlet 22 with an overhanging lip 23 which directs the blast of air into a slot 24 at that 80 side of the ring 25 and the sound is emitted from the perforations 26 around the edge of the ring and they are adapted to be closed by the fingers of the two hands as the device is held to the mouth. One end of the ring is 85 closed by a partition 27 so that as the blast travels around the ring the sound passes outward and is varied according to the distance traversed by the air and the outlet opened.

90 What I claim as new is:

1. In a toy, the combination of a tube having outlets and formed as a ring at one end and whose other end is a radial extension of the ring portion, and a mouth piece and 95 inlet in the extension.

2. In a toy, the combination of an endless tube having outlets and one end formed as a ring, and a radial extension comprising the other end of the tube and having an inlet. 100

3. In a toy, the combination of a tube comprising a straight portion with a circular end part and having an inlet at the end of the straight portion and a plurality of outlets in the circular part, and a tangential 105 mouthpiece at the inlet.

4. In a toy, the combination of a perforated tube straight at one end and terminating in a circular part at the other end, a telescopic part sliding in the straight end 110 and having an inlet, and a mouthpiece at the inlet.

5. In a toy, the combination of a telescopic tube with a circular portion at one end and having outlets, a movable tube in the other end of the tube, and a tangential mouth piece.
6. In a toy, the combination of a straight tube terminating in a circular tubular por-

tion with outlets, and a tangential mouth piece with a notch and located at the other end of the tube.

Signed at New York, in the county of New York and State of New York, this 28th day of December, A. D. 1918.

SIGMUND F. KOHN.
